UNITED STATES PATENT OFFICE.

CLAUDE C. READ, OF DETROIT, MICHIGAN.

DOORSTOP.

Application filed September 8, 1922. Serial No. 586,856.

My invention relates to a new and useful improvement in a door stop and has for its object the provision of a door stop which will be simple in structure, economical of manufacture and highly efficient in use.

Another object of the invention is the provision of a door stop constructed on the principle of a hinge and adapted for folding out of operative position.

Another object of the invention is the provision of a door stop adapted for use with doors designed to swing outwardly over uneven surfaces.

Another object of the invention is the provision of a door stop constructed on the principle of a toggle and adapted to engage the surface acted upon previous to swinging to or beyond center.

Another object of the invention is the provision of a door stop embodying the toggle and having means for preventing the swinging of the stop member beyond center.

Other objects will appear hereinafter.

The invention consists in the combination and arrangement of parts hereinafter described and claimed.

The invention will be best understood from a reference to the accompanying drawings which form a part of this specification and in which,

Fig. 1 is an elevational view of a door embodying the invention,

Fig. 2 is a side elevational view of the invention applied to a door,

Fig. 3 is a top plan view of the invention,

Fig. 4 is an elevational view of an extension member used in the invention, and,

Fig. 5, is a side elevational view, with parts in section, showing the extension applied.

The invention is designed for use with swinging doors and serves as a means for preventing the undue closing of the door after the same has been opened. It is particularly useful in connection with barns, garages, etc. although it will appear quite evident from the description that the invention is equally as well adaptable for use with all kinds of swinging doors and may be used with any door in a house or office building when the door is of the swinging type.

The invention comprises a body portion 7 which is made from a single blank and is provided with laterally extending flanges 8 and 9, the flanges being connected to the

body portion by inwardly projecting walls 18 and 19, thus causing the flanges to lie in a different plane than the flat surface of the body portion. The lower end of the body portion 7 is provided with a tongue which is curled to form knuckle 10. A co-operating member 11 is provided having a comparatively narrow tongue at each side thereof, each of which is curled to form a knuckle 12 and 13. A tongue projects outwardly from said knuckles, said tongue 14 serving as an abutment to limit the swinging movement of the member 11. The extreme end of the member 11 is turned down downwardly as at 15. The body portion 7 is adapted for attachment to a door 16 by means of bolts and screws 17. Projected through the knuckles 10, 12 and 13 is a pintle 20 so as to allow the member 11 to swing relatively to the member 7.

When the device is inoperative the member 11 is swung to the position shown in Fig. 1. When it is desired to use the device the member 11 is swung into the position shown in Fig. 2, thus permitting the points 15 to engage the ground or flooring over which the door is swung. If it is desired to use the device on a door inside of a building the point 15 may be capped with a rubber or cork tip or some other non-abrasive material.

Sometimes a door is swung over an uneven surface and to accommodate the device to this uneven surface, I have provided an extension 21 which is secured to the member 11 by suitable bolts 22 and is provided at its outer end with a metal engaging tip 23.

It will be noted that as the door tends to swing closed the member 11 grips the surface and the tendency is to cause the member 11 to approach the centre, thus binding itself more firmly against the surface engaged, the principle involving the toggle joint.

While I have illustrated and described the preferred form of construction, I do not wish to limit myself to the precise form of structure shown, but desire to avail myself of such variations and modifications as come within the scope of the appended claim.

Having thus described my invention, what I claim as new and desire to secure by Letters Patent is:

A door stop of the class described comprising a channel shaped supporting member deeper at one end than at the other, and hav-

ing the edges of the end walls angularly turned to provide outwardly projecting aligning flanges at opposite sides for attachment to a supporting surface; a knuckle formed on the lower edge of the base of said supporting member centrally thereof; a stop member comprising a straight main body portion; knuckles formed on said main body portion at opposite sides thereof for embracing the knuckle on said supporting member; a pintle projected through said knuckles for hingedly mounting said main body portion on said supporting member; a tongue pro-

jecting outwardly from said main body portion between said knuckles and curved, intermediate its ends, for permitting engagement of the same with said supporting member when moved to a predetermined position relatively thereto, said tongue projecting into the deeper end of said channel between the base of said supporting member and the supporting surface. 15
20

In testimony whereof I have hereunto set my hand at Detroit in the county of Wayne and State of Michigan.
